UNITED STATES PATENT OFFICE.

EDWIN CROMPTON AND CHARLES L. CROOKS, OF PUEBLO, COLORADO.

COMBINED LATCH AND LOCK.

1,355,735.

Specification of Letters Patent. Patented Oct. 12, 1920.

Application filed August 5, 1918. Serial No. 248,320.

To all whom it may concern:

Be it known that we, EDWIN CROMPTON and CHARLES L. CROOKS, citizens of the United States, residing at Pueblo, in the 5 county of Pueblo and State of Colorado, have invented certain new and useful Improvements in Combined Latches and Locks; and we do hereby declare the following to be a full, clear, and exact description 10 of the invention, such as will enable others skilled in the art to which it appertains to make and use the same.

Our invention relates to combined latches and locks generally and, in some of its aspects, more particularly to latches for use 15 on automobile and similar doors.

The principal object of our invention is to provide a simple combined latch and lock in which the latching and locking operations 20 are automatically performed by the act of closing the door, and in which the unlocking and unlatching operation may be performed without the use of keys or similar devices by depressing a single operating 25 member.

In its broader aspects, our invention comprises a casing that is adapted to be mounted on or within a door jamb. The casing 30 encloses the operatively connected portions of the elements which include a locking or latching bolt resiliently projecting from the casing in the normal position of the device, and a second bolt normally projecting from the casing and adapted to lock or dog a 35 spring-pressed plunger which, when released, engages and locks or dogs the locking or latching bolt.

The objects and novel features of the invention will be apparent from the following 40 description taken in connection with the drawing in which—

Figure 1 is a vertical sectional view of a 45 combined latch and lock embodying our invention, the parts being shown in normal or unlocked position, and the keeper carried by the door being shown as about to move into closed position;

Fig. 2 is a vertical sectional view similar 50 to Fig. 1, except that the keeper is shown in position with the parts in latched and locked position;

Fig. 3 is a transverse vertical section, taken on the line 3—3 of Fig. 2;

Figs. 4 and 5 are horizontal sectional 55 views taken, respectively, on the lines 4—4 and 5—5 of Fig. 2; and

Fig. 6 is a face view of the keeper that is adapted to be attached to the door.

Referring to the drawing, 10 designates the casing that contains most of the operating mechanism of the device, the casing comprising side plates 11 formed integral with an end plate 12 to which the face plate 13 is secured. The end plate 12 and face plate 13 are provided with registering 60 apertures 14 and 15, arranged vertically above one another and providing openings through which the bolts A and B are projected in the normal or unlocked position 65 of the device.

The bolt A serves to lock or dog and release a locking and unlocking plunger P and a front portion 16 thereof is substantially rectangular in cross section and is 70 slideable in the apertures 14, and a rear reduced portion 17 is slideable in an aperture 18 in line with the apertures 14 and located in a cross brace 19 secured to the side plates 11. A spring 20 surrounds the reduced portion 75 17 of the bolt A and bears against a shoulder 21 and against the inner face of the cross brace 19, tending to project the bolt through the apertures 14. The outward movement of the bolt A is limited by a stop pin 22 carried by the bolt.

The bolt B has a semi-spherical head 23 that projects outwardly through the apertures 15 and is carried by a shank 24 that is substantially rectangular in cross section and is slideable in an aperture 25 in the cross brace 26 in line with the apertures 15. The brace 26 is below the brace 19 and also secured to the side plates 11 of the casing. The casing is thus substantially open at the rear except for these braces. A spring 27 surrounds the rear end of the shank 24, one 80 end thereof bearing against the inner face of the cross brace 26 and its opposite end bearing against a pin 28 carried by the bolt. The spring 27 resiliently presses the bolt B 85 outwardly to project the knob 23 from the face plate of the casing, the outward movement of the bolt being limited by an enlargement 29 carried by the bolt.

The locking and unlocking plunger P consists of a comparatively long rod substantially rectangular in section and is reciprocable in guides formed by apertures 30 and 31 in cross braces 32 and 33. The lower end of the plunger P is reduced as at 34 to 100 provide a shoulder 35 forming a bearing for the upper end of the actuating spring 36.

which surrounds the reduced part of the plunger and has its lower end supported on the upper side of the cross brace 33. A cotter pin carried by the plunger below the cross brace 37 limits the upward movement of the plunger. The plunger P extends upwardly out of the casing and a knob 38 on the upper end thereof is so accessible that the plunger may be manually operated to 10 unlock the door.

The plunger P has two square-shoulder notches 40 and 41 in one side thereof, the upper notch 40 being disposed so as to receive a portion of the rectangular part of 15 the dogging bolt A when the latter is in its normal or projected position as seen in Fig. 1. The engagement of the notch 40 of the plunger P by the bolt A locks or dogs the plunger in a depressed position and compresses the spring 36, storing energy in the latter so that when the bolt A unlocks the plunger, the latter will be projected upwardly to lock or dog the bolt B. The bolt A is provided with a square-shoulder notch 42 of a size and depth to permit the 20 upward movement of the plunger past the bolt when the latter is retracted. At the same time a portion of the plunger moves into the notch 42 and locks or dogs the bolt A against outward movement until the 25 plunger is again depressed.

In the normal or unlocked position of the device as shown in Fig. 1, the bolt B is freely movable inward against the pressure of the 30 spring 27 since the notch 41 of the plunger registers with the shank 24 of this bolt. The shank 24 also has a square-shouldered notch 35 43 in the side thereof facing the plunger so that in the normal unlocked and unlatched position of the device the plunger may move transversely of the bolt B. Upon release of the plunger by the inward 40 movement of the bolt A, the spring 36 moves the same upwardly and a portion of the plunger below the notch 41 enters the notch 43 on the bolt B, thereby locking or 45 dogging the latter against movement inwardly or outwardly.

A keeper designed for use with the latch and lock embodying this invention is shown 50 in Fig. 6, and comprises a face plate 45 attachable to the edge of a door. The plate has a channel portion 46 provided with a cam surface 47 that is adapted to engage the curved projecting end 48 of the bolt A. The 55 plate also has formed integrally therewith a lip 49 disposed in advance of a depression or socket 50 adapted to receive the knob 23 on the bolt B. The lip 49 has an inner cam surface 51 by means of which the knob is 60 retracted upon closing the door to permit it to pass over a shoulder 52 that locks or latches it in place.

Assuming the lock and latch to be in its 65 normal or unlocked position as shown in Fig. 1, the operation of the device is as fol-

lows: Upon closing the door carrying the keeper, the knob 23 is depressed to permit it to pass over the shoulder 52 and at the same time the bolt A is being forced inwardly by the cam 47. After the knob 23 of the bolt B snaps into the socket 50, the notch 42 on the bolt A moves into register with the plunger, releasing the latter, which is shot upwardly by the spring 36. This moves the plunger so that a portion thereof will be located in the notch 43 of the bolt B, locking or dogging the knob 23 of the latter in the socket 50, as shown in Fig. 2.

In order to open the door, the button 38 is pressed downwardly forcing the plunger 80 into the position in which the notch 41 registers with the shank 24 of the bolt B, whereupon the door may be opened by gently pushing the same outward. The bolt A will thereupon be shot out by the spring 85 20 and will lock the plunger in its depressed or normal position.

While we have shown and described our combined lock and latch in detail it is to be understood that various features thereof 90 may be modified without departing from the spirit of the invention.

What we claim is:

1. A latch comprising a locking and unlocking plunger, means releasable by a keeper for retaining said plunger in unlocking position, a bolt, said plunger being adapted to engage said bolt, and means whereby the plunger is moved into position to lock said bolt when said retaining means is released.

2. A latch comprising a locking and unlocking plunger, two bolts adapted and arranged for engagement by keeper means, said bolts being movable transversely of said plunger, one of said bolts releasably locking said plunger in said position, and means whereby the plunger is moved into position to lock the other bolt when said locking bolt is released.

3. A latch comprising two bolts adapted and arranged for engagement by a suitable keeper on a door jamb, a plunger, and means whereby said plunger is normally releasably locked or dogged by one of said bolts, and adapted to engage and lock or dog the other bolt when released by the operation of the first mentioned bolt.

4. A latch comprising two bolts, a plunger extending across both bolts and having means at one end for manually operating it, means whereby said plunger is releasably locked or dogged by one of said bolts, means whereby the other bolt is locked or dogged by said plunger when the latter is released, and means for actuating the plunger when it is released.

5. A latch comprising a depressible plunger, an actuating spring surrounding the same in which energy is stored when said

- plunger is depressed, means for releasably locking said plunger in its depressed position, a bolt, and means whereby said bolt is locked when said plunger is released.
- 5 6. A latch comprising a plurality of notched bolts, and means, comprising a notched plunger extending across both bolts, whereby one bolt controls the movement of the other bolt.
- 10 7. A latch comprising a plurality of spring-pressed notched bolts arranged one above the other, and a spring-pressed notched plunger extending above the upper bolt, the arrangement being such that one 15 of said bolts locks or dogs said plunger in the normal position of the device and said plunger is actuated to lock or dog the other bolt when the plunger is released by a movement of the bolt that normally locks or 20 dogs it.
8. A latch comprising a depressible plunger, an actuating spring therefor in which energy is stored when said plunger is depressed, a spring-pressed bolt for releasably 25 locking or dogging said plunger in its depressed position, and a second bolt, both of said bolts extending across said plunger and being movable transversely of said plunger in the depressed position of the latter, and 30 the plunger being automatically moved into position to lock or dog said second bolt when the other bolt releases said plunger.
9. A latch comprising a depressible plunger having two notches, a depressible bolt 35 engaging a shoulder formed by one of said notches and locking or dogging said plunger in depressed position in the normal condition of the device, said bolt having a notch
- through which said plunger is movable when released, a second bolt normally depressible 40 through the other notch in said plunger, and having a notch providing a shoulder adapted to engage a part of said plunger when the latter is released, whereby said second bolt is locked or dogged, and means 45 for actuating said plunger.
10. A latch comprising a casing, a locking and unlocking plunger having a part disposed within said casing and a part at its upper end accessible from the exterior of 50 said casing for manually depressing the plunger, an actuating spring therefor in which energy is stored when said plunger is depressed, means for releasably locking said plunger in its depressed position, a bolt having 55 a head projecting from said casing and a shoulder within the casing, the arrangement being such that a part carried by said plunger engages said shoulder to lock said bolt when the said locking means is released. 60
11. In a lock, the combination of a locking bolt, a spring surrounding said bolt for actuating it, a device for retaining said bolt in its locking position, such device being removable to release or unlock said bolt, a 65 spring surrounding said device for moving the same to lock said bolt, means for retaining said device in the position in which it releases or unlocks said bolt, and a spring surrounding such retaining means for operating the same. 70

In testimony whereof we hereunto affix our signatures.

EDWIN CROMPTON.
CHARLES L. CROOKS.
